Filed Dec. 17, 1963, Ser. No. 331,235

4 Claims. (Cl. 175—4)

This invention relates to apparatus for obtaining solid samples of earth formations and, more particularly, pertains to a new and improved core-taking apparatus for obtaining a solid sample of earth formation material.

Generally, cores or samples of earth formation material are obtained by lowering a side wall sample taker assembly into the borehole to the level of the formation to be investigated. The sample taker assembly includes a gun body which receives a number of hollow core-taking bullets together with explosive means which are selectively operable so that the bullets may be impelled towards and into a formation, with the hollow interior of the bullets thereby receiving the formation material. Usually, the core bullet is secured to the gun body by one or more flexible retrieving connections so that a pull, as by raising the gun body, serves to withdraw the core bullet with a formation sample from the earth formations. Thus, a formation core sample can be retrieved to the surface of the earth for examination and testing.

However, many problems are presented by the variety of formations which are encountered in sampling operations. For example, the types of formations may be generally classified as (1) soft, (2) medium, (3) firm, (4) hard, and (5) extra hard. Thus, the problems may vary from the difficulty in getting the bullet into the extra hard formations without damage to the difficulty encountered in soft formations in the withdrawal of the core bullet from the formation. To obtain core samples from the various types of formations, different types of core bullets have been designed to meet the various conditions arising. Aside from the problem of retrieving the core bullet, it is, of course, necessary to obtain a core sample which is representative of the formation tested.

Particularly in the soft to firm formations, recovery of core bullet has been facilitated by providing the core bullet with a separable forward portion in the form of an annular cutting ring which generally has a slightly greater outer diameter than the core barrel. Thus, the ring forms an enlarged hole relative to the body of the bullet to alleviate "sticking" of the bullet body in the formation. When a pull is exerted on the body of the bullet, it should separate from the cutting ring thereby to leave the cutting ring in the formation. Various cutting ring attachments have heretofore been used such as the types disclosed in Patents No. 2,923,530, No. 3,101,797 or No. 3,072,202.

It has been found in many instances that the core bullet becomes so firmly embedded that in pulling on the bullet in the formations, the wire-retrieving connections are broken.

Accordingly, it is an object of the present invention to provide new and improved core-taking apparatus for minimizing the retrieval pull required on a core-taking bullet.

Another object of the present invention is to provide new and improved core-taking apparatus which is self-retracting from earth formations.

Still another object of the present invention is to provide new and improved core-taking apparatus which is hydraulically self-retracting from earth formations.

In apparatus for obtaining a core sample, in accordance with the present invention, a gun body receives one or more core-sampling bullets which may be disposed

2

lengthwise of the gun body. The bullet is adapted to be impelled toward and into earth formations by explosive means and has a body member with a cutting ring member releasably received on its forward end. Means are provided to operate after the bullet has left a gun body and is in the earth formations to move the body member rearwardly relative to the ring member. Thus, the body member is retractable from earth formations relative to the ring member independent of the usual retrieving wire members.

The novel features of the present invention are set forth with particularity in the appended claims. The present invention, both as to its organization and manner of operation together with further objects and advantages thereof, may best be understood by way of illustration and example of certain embodiments when taken in conjunction with the accompanying drawings in which:

FIG. 1 is a view in partial cross-section of apparatus embodying the present invention for obtaining a core sample and illustrated in a well bore;

FIG. 2 is a view in cross-section of a bullet embodying the present invention; and

FIG. 3 is a view in cross-section of a bullet embodying another form of the present invention.

In FIG. 1 of the drawings, there is shown a gun block or body 10 disposed in a borehole 11 opposite a formation 12 of interest. Usually, borehole 11 contains a drilling mud 13.

Gun block 10 has a cylindrical bore 14 adjoining a bore 15 of smaller diameter, the bore 15 forming a powder chamber which terminates short of the rear surface 16 of the gun block. Chamber 15 contains an appropriate and conventional explosive propellant 17 while bore 14 receives a generally cylindrical core-taking device or bullet assembly 18 constructed in accordance with the present invention. Although not illustrated, gun block 10 generally contains additional bullet assemblies in respective bores distributed along a vertical axis for the gun block.

Bullet assembly or bullet 18, near its rearward end, has an annular groove which receives an O-ring 19 to provide a fluid-tight seal for the bullet assembly 18 in the bore 14, and flexible retrieving wires 20 are secured in a conventional manner between the bullet assembly 18 and gun block 10 to permit the bullet body of the assembly to be retrieved. A conventional igniter 21 suitably mounted in the block 10 may be employed to detonate the explosive propellant 17 and thereby propel the bullet 18 toward and into the formation.

Referring now to FIG. 2, bullet or bullet body member 18 includes a central tubular sample-receiving core part 21, with an attached rearward bottom part 22. Forward part 21 has a forwardly facing shoulder 24 and releasably receives a cutting ring or release member 25. A snap ring 26 is provided to insure retention of ring 25 on part 21. Ring member 25 has the usual, conically shaped forward surface and is disposed slightly rearwardly of the forward cutting edge 27 on the tubular part 21. Ring member 25 is also slightly greater in overall diameter than the diameter of the body portion rearwardly of the cutting ring member to reduce the area of the bullet in the formation subject to hydrostatic pressure.

The purpose of the cutting ring member 25 is to provide an oversized hole so that the outer body of the bullet 18 is prevented from intimate contact with the earth formations, the ring member 25 being left embedded in the earth formations. Of course, the precise connection and arrangement of the ring member relative to the bullet body is immaterial to the present invention so long as the ring member when in the earth formations is releasable from the bullet body. The above-

described ring arrangement, however, is preferable since the forward end of part 21 extends beyond ring 25 and obtains a better core sample more reliably.

Tubular core part 21 also has ports 28 in its side walls and connections 29 (FIG. 1) for attachment of retrieving wire elements 20 to the bullet body.

Bottom part 22 provides a bottom 30 for the tubular core part 21 and has an O-ring seal 31. Bottom part 22 also has stepped flanged portions 32, 33. Flanged portion 32 forms a piston which is slidably and sealingly received in gun bore 14 by means of the O-ring 19. An inner, self-releasing sleeve 35 abuts the shoulder formed on flange portion 33 and an outer actuating sleeve 36 abuts the shoulder formed on flange portion 33. Inner sleeve 35 terminates at forward shoulder 24 while outer sleeve 36 abuts ring member 25 and spaces the ring member a short distance above shoulder 24. Access ports 37, 38 are provided to accommodate connections 20 and ports 28 where necessary.

Intermediate of flanged portion 33 and forward shoulder 24 a portion of the part 21 is reduced in diameter at 39 to slidably and sealingly receive a piston portion 40 of the self-releasing sleeve 35. Piston portion 40 has internal and external grooves receiving the O-rings 41, 42 so as to seal relative to part 21 and outer sleeve 36. An O-ring 43 is provided on part 21 above the recessed portion 39 to seal the part 21 relative to sleeve 35. A chamber 44 is formed between sleeve 35 and parts 21 and is pressure sealed by the O-rings 41, 43. Sleeve 35 has an end surface 45 which is adjacent but not in contact with the cutting ring member 25. Flanged portion 33 also has an O-ring 46 providing a seal between portion 33 and outer sleeve 36. Sleeve 36 has an internal annular recess at 47 weakening the structure of the sleeve. The lower end of piston portion 40 is recessed at 48 and adapted for fluid connection to recess 47, as by a passage 48a.

In operation, when the powder 17 is ignited, the bullet is accelerated from bore 14 toward and into adjacent earth formations. Snap ring 26 is displaced from its groove leaving the cutting ring 25 free, the cutting ring staying on the bullet body due to the forward movement of the bullet body. As the forward end of the bullet penetrates the formation, the cutting ring makes a large hole and keeps the portion of the bullet and sleeve 36 rearwardly of the ring from intimate contact with the formation. When ring member 25 impacts with the earth formations, weakened section 47 of outer sleeve 36 fails and lets hydrostatic pressure into chamber 48. Chambers 48 and 44, it will be recalled, had previously been sealed from the hydrostatic pressure by seals 42, 46, 41, 43, 31. There will be a force produced by the hydrostatic pressure to slide self-releasing sleeve 35 axially along part 21 into engagement with ring 25. This force is equal to the area bounded by the seals 43, 41 times the hydrostatic pressure. The self-releasing sleeve 35 will then press against the ring 25 and part 21 will be driven out of the formation by an equal and opposite force for retrieval by the fasteners 20, (FIG. 1).

FIGURE 3 shows another bullet assembly that will perform the same function as the bullet shown in FIGURE 2. The principal difference is in the valve means to allow the hydrostatic pressure to act on an unbalanced area after the bullet has struck the formation. Connections 29 and access ports are not shown for clarity of illustration.

As shown in FIG. 3, an outer sleeve 50 is provided and together with seals 43a, 41a, 46a, 31 and parts 21, 22 form sealed-off chambers 44 and 48. A rod member 51 extends longitudinally between ring member 25 and a break valve 52 in sleeve 50. Break valve 52 is adapted to be sheared open upon the application of sufficient force via rod member 51 to place the chamber 48 in fluid communication with hydrostatic well pressure exterior of the bullet.

In operation, the bullet strikes the formation and the deceleration inertia causes the rod member 51 to press against the break valve 52 and rupture it. When break valve 52 is ruptured, hydrostatic pressure is allowed into chamber 48. Chambers 48 and 44 have previously been sealed from outside pressure by the various seals. When hydrostatic pressure is permitted in chamber 48, there is a force applied to slide sleeve 50 in relation to part 21. This force is equal to the area bounded by seals 43a, 41a times the hydrostatic pressure. In this manner ring member 25 is left in the formation as part 21 is withdrawn. The assembly is retrieved by the fasteners attached to the gun, (FIG. 1).

While particular embodiments of the present invention have been shown and described, it is apparent that changes and modifications may be made without departing from this invention in its broader aspects and, therefore, the aim in the appended claims is to cover all such changes and modifications as fall within the true spirit and scope of this invention.

What is claimed is:

1. A formation core-taking device adapted to be fired from a gun body into earth formations about a well bore comprising: a tubular core-taking body member having a forward end, a formation-cutting ring member releasably received on said forward end, means operatively coupled between said body member and said ring member and responsive to hydrostatic pressures after ejection from a gun body for providing a force on said ring member, and means for admitting hydrostatic pressures to said hydrostatic pressure-responsive means in response to impact of said core-taking device with earth formations to urge said body member and said ring member in opposite directions relative to one another when said ring member and forward end of said body member are embedded in earth formations.

2. A formation core-taking device adapted to be fired from a gun body into earth formations about a well bore comprising: a tubular core-taking body member having forward and rearward ends and a reduced-diameter intermediate portion; a formation-cutting ring member releasably received on said forward end; means responsive to hydrostatic pressure for releasing said ring member including a slidable sleeve member around said body member and adapted for forward travel to release said ring member and means fluidly sealing said sleeve member to said body member for providing sealed forward and rearward annular chambers around said intermediate body portion between said body ends; and means responsive to impact with earth formations for admitting hydrostatic pressure into said rearward chamber to urge said sleeve member forward and said body member rearwardly when said forward body end is embedded in earth formations.

3. A formation core-taking device adapted to be fired from a gun body into earth formations about a well bore comprising: a tubular core-taking body member having forward and rearward ends and a reduced-diameter intermediate portion; a formation-cutting ring member releasably received on said forward end; means responsive to hydrostatic pressure for releasing said ring member including a slidable first sleeve member around said body member and adapted for forward travel to release said ring member and means fluidly sealing said first sleeve member to said body member at longitudinally spaced intervals for providing sealed forward and rearward annular chambers around said intermediate body portion between said body ends; passage means for admitting hydrostatic pressure into said rearward chamber; and means normally sealing said passage means and responsive to impact with earth formations for admitting hydrostatic pressure into said passage means, said impact-responsive means including a second sleeve member covering said passage means and having a weakened portion adapted to fail under a predetermined force and a forward portion

for transmitting impact forces to fail said weakened portion and admit hydrostatic pressure into said rearward chamber to urge said first sleeve member forwardly and said body member rearwardly when said forward body end is embedded in earth formations.

4. A formation core-taking device adapted to be fired from a gun body into earth formations about a well bore comprising: a tubular core-taking body member having forward and rearward ends and a reduced-diameter intermediate portion; a formation-cutting ring member releasably received on said forward end; means responsive to hydrostatic pressure for releasing said ring member including a slidable sleeve member around said body member and adapted for forward travel to release said ring member and means fluidly sealing said sleeve member to said body member at longitudinally spaced intervals for providing sealed forward and rearward annular chambers around said intermediate body portion between said body ends; passage means for admitting hydrostatic pressure into said rearward chamber; and means normally sealing said passage means and responsive to impact with

5 earth formations for admitting hydrostatic pressure into said passage means, said impact-responsive means including a closure member sealing said passage means, said closure member having a weakened portion adapted to fail under a predetermined force, and means engaged with said weakened portion for transmitting impact forces thereto to fail said weakened portion and admit hydrostatic pressure into said rearward chamber to urge said sleeve member forwardly and said body member rearwardly when said forward body end is embedded in earth formations.
